UNITED STATES PATENT OFFICE.

MACKINTOSH HUTCHINSON, OF TORONTO, ONTARIO, CANADA.

WOODWORKING-MACHINE.

1,283,196.

Specification of Letters Patent. Patented Oct. 29, 1918.

Application filed March 7, 1918. Serial No. 220,993.

To all whom it may concern:

Be it known that I, MACKINTOSH HUTCHINSON, a subject of the King of Great Britain, residing at Toronto, in the Province of 5 Ontario and Dominion of Canada, have invented certain new and useful Improvements in Woodworking-Machines; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

My invention relates to wood working machines, adapted, among other uses, for sawing in mitering, cross-cutting, dadoing and kindred operations, and adapted to have 20 its motor coupled-up with a machine for ripping, for sandpapering and for other purposes so that combined operations can be carried out by operatively connecting-up with the sawing machine the necessary parts for 25 carrying out the other operations.

The object of the present invention is to improve various features of the machine so as to afford greater ease and facility of operation in its various parts, and also increase 30 its stability, and durability and compactness.

To the accomplishment of the foregoing and such other objects as may hereinafter appear the invention consists in the features 35 hereinafter particularly described and then sought to be clearly defined by the claims, reference being had to the accompanying drawings forming a part hereof, and in which—

40 Figure 1 is a central vertical section through the machine, with some parts broken away and others omitted;

Fig. 2 is a plan view, enlarged scale, of the traveling frame or carriage and its supporting bracket;

Fig. 3 is a side elevation of the same parts, with one of the bars or rods of the carriage broken away;

Fig. 4 is an end view of the carriage supporting bracket, looking at the end which carries the saw spindle;

Fig. 5 is a cross section through the carriage and supporting bracket on the line 5—5 of Fig. 3, looking in the direction of the 55 arrows;

Fig. 6 is a horizontal section on the line

6—6 of Fig. 1 showing the means for clamping the post in position;

Fig. 7 is a side view of one of the eccentric spindles for supporting the ball bearing rollers which sustain the side rods of the traveling carriage;

Fig. 8 is an end view of the spindle;

Fig. 9 is one of the sustaining rollers, shown in cross section;

Fig. 10 is a side elevation of a portion of the machine illustrating the motor and the carriage, and the positive lock for angular adjustment of carriage and saw;

Fig. 11 is a plan view of the angular adjusting collar.

The table will consist of upright metal corner legs connected together and braced by horizontal tie members 1 and provided with a work supporting top 2. To give greater 75 rigidity and afford a support for an upright post or column 3 from which the traveling carriage is sustained, a metal frame comprising horizontally disposed upper and lower members 4 and 5 and end members 6 and 7, 80 is disposed centrally beneath the table, the member 7 being extended diagonally beyond the end of the table where the column 3 is located so as to brace the table and column and afford greater stability at the point 85 where the column and the parts which it sustains are positioned. The base of the column 90 rests in a collar 8 secured to the member 5 and is encircled by a split sleeve 9 attached to or made as a part of the member 4, the sleeve being formed with threaded ears 10 through which pass the threaded end of a rod 11 provided with a hand wheel 12 so that, if desired, the sleeve may be made to clamp to column to hold it to any circular 95 adjustment that may be given thereto for some desired angular adjustments of the saw that will be carried by its mandrel on the traveling carriage that will be sustained from the column.

100 On the column, above the table top, is a bracket for supporting the traveling carriage in which the saw is mounted. This bracket consists of a sleeve 13 encircling the column and formed with recesses 14 which receive steel guide bars 15 riveted or otherwise secured to opposite sides of the column so as to permit of vertical adjustment of the carriage to regulate the depth of cut of the saw mounted on the carriage. The 105 bracket sleeve has side sleeves 16 to receive side rods of the carriage and also a hori-

zontally extending member 17 which at its rear is provided with boxes 18 designed to receive and guide the side rods of the traveling carriage, and thus the carriage is supported at a point adjacent to the column and also at a point relatively remote therefrom. To reduce friction and insure an easier and smoother movement of the carriage, the boxes 18 are provided with rollers 19, which 5 preferably have concave faces, to afford a rotatable rest or seat for the side rods of the carriage. The opposite ends of these rollers are bored out and fitted with races 21 between which are fitted ball bearings 22, thus 10 affording anti-friction bearings between the rollers and their spindles 23 which pass through the rollers and are supported in the boxes 18 and held in position therein by set screws 24. To maintain the carriage level 15 and insure an even uniform pressure of the side rods of the carriage on the rollers under varying conditions, provision is made for vertical adjustment of the rollers, so that they may be elevated or lowered as found 20 desirable, by turning or forming the spindles eccentrically as illustrated. Thus, to elevate or lower the rollers so as to obtain the desired pressure between the rollers and rods of the carriage, it is only necessary to 25 loosen the set screws which hold the spindles and then partially rotate the spindles in the direction to raise or lower the rollers as desired, and then tighten the set screws to grip and hold the spindles and rollers to the 30 adjustment given. This is an important feature in maintaining the even smooth movement of the carriage to insure the best work.

The carriage is made up of the side rails or rods 25, which are preferably made of 35 steel, and a connecting cross-head 26 which is formed with sleeves 27 to receive the side rods which are secured within the sleeves 27 to receive the side in any suitable manner so that the cross-head and the rails or rods 40 will move together, the head being provided with a hand grip 28 by which the workman may move the carriage to draw the saw through the work. The cross-head also carries two-part boxes 29 in which is journaled 45 the saw mandrel or arbor 30 to one end of which a saw 31 will be attached and to the other end of which will be attached a pulley 32 or other means which will derive power 50 through a belt 33 or other means connected 55 with the shaft of a motor 34, electric or otherwise which may be suitably supported on the opposite end of the carriage so as to be moved with the carriage.

To adjust the depth of cut of the saw the 60 bracket which supports the carriage is adjusted vertically by means of a threaded rod 65 threaded in the bracket extension 7, the rod extending through a guide brace bracket 36 and having a bevel pinion 37 at its upper 70 end with which pinion meshes another pin-

ion 38 on the end of a shaft 39 having a hand wheel 40 so that through such means the bracket and saw carrying carriage may be vertically adjusted to regulate the depth of cut of the saw.

For the purpose of holding the saw so as to cut square, or at an angle of 45 degrees, or at right angles, either to the right or to the left, I provide the post 3 with a collar 41 and provided with apertured ears 42, preferably five in number, adapted to receive a pin 43 which will pass through the desired ear and enter a hole 43^a formed in a suitable part of the table frame of the machine, for instance in the central rail 4, so that the 75 post will be positively held by the pin to the adjustment which will secure the saw in position to cut either square or at the angle desired to which the adjustment is made. The collar will be held to the post by a set screw 80 44, preferably for cutting square in the direction from front to rear of the table. By removing the locking pin and turning the post to bring another ear to register with the pin receiving hole in the table frame and 85 then inserting the locking pin, a cut in the direction desired may be obtained either to the right or left and at the angle or extent of adjustment provided for. The top of the 90 table will be preferably recessed to receive 95 the collar. If a cut at an angle other than that provided for by the positive locking collar is desired the same may be effected by removal of the locking pin, then turning the post to the position desired and then 100 tightening the encircling clamp-ring 9 by means of the screw rod 11, so as to hold the post by frictional clamping action instead of by the positive lock afforded by the collar and locking pin. At other times when not 105 serving as a clamp, the ring 9 serves as a brace to the post.

The saw arbor and the driving motor both being fixedly attached to the traveling carriage there will be no slackening or disarrangement of the belt or driving connection between the motor and saw mandrel in either the vertical or horizontal adjustment of the carriage and saw; the rear extension of the carriage supporting bracket with the bearings for the side rods of the carriage relieve the side rods of the strain of weight of the motor carried by the rods and also make the movement of the carriage and parts supported by it easier, smoother and under more 110 uniform pressure than otherwise would be the case; the rigidity of the column in relation to the work table is greater by reason of the holding clamp provided, and also by reason of the centrally disposed bracing 115 frame beneath the table top.

The numeral 45 designates an electric switch that may be used with electric conductors for supplying the current for running the electric motor for driving the saw 120 125 130

mandrel and is not shown in detail as no claim is made to such feature.

Having described my invention and set forth its merits what I claim is:

- 5 1. A wood working machine, comprising an upright post, a bracket adjustable axially of the post, provided with side sleeves and a member extending horizontally from the bracket provided at each side with boxings 55
- 10 10 a saw traveling carriage comprising side rods supported by the sleeves to the bracket and the boxes of the extending member and a head-piece connecting the rods together at one end and provided with bearings supporting a saw mandrel. 15
- 15 2. A wood working machine, comprising an upright post, a bracket adjustable axially of the post and provided with a member extending horizontally from the bracket and 20
- 20 provided at opposite sides with boxings, a saw traveling carriage comprising side rods supported by the boxings of the extending member and by sleeves connected to the bracket, a saw mandrel supported from the carriage, and rollers fitted in the boxings of the extending member beneath the side rods of the carriage to form roller seats for the rods, and means for vertical adjustment of the rollers. 25
- 25 3. A wood working machine, comprising an upright post, a bracket associated with the post, a member extending horizontally from the bracket and provided at opposite sides with boxings, a saw traveling carriage 30
- 30 comprising side rods supported by the boxings of the extending member and by sleeves connected to the bracket, a saw mandrel supported by the carriage, rollers fitted in the boxings of the extending member beneath 35
- 35 the side rods of the carriage to form seats for the rods, and eccentrically formed spindles supporting the rollers and providing for vertical adjustment of the rollers. 40
- 40 4. A wood working machine comprising an upright post, a bracket associated with the post, a member extending horizontally from the bracket and provided at opposite sides with boxings, a saw traveling carriage 45
- 45 comprising side rods supported by the boxings of the extending member and by sleeves
- connected to the bracket, a saw mandrel supported by the carriage, rollers fitted in the boxings of the extending member beneath the side rods of the carriage to form seats for the rods, said rollers having ball bearing 55
- 55 races fitting therein, and eccentrically formed spindles supporting the rollers and providing for vertical adjustment of the rollers. 60
- 60 5. A wood working machine, comprising a table, an upright rotatable post extending above and below the top of the table, a traveling saw carriage provided with a saw mandrel supported from the post and adjustable axially thereof, a rigid bracing frame disposed beneath the table top, provided at one end with a diagonally extending leg and having a horizontally extending member constituting a support for the lower end of the upright post, and a clamp for holding 65
- 65 the post to its rotatable adjustment. 70
- 70 6. A wood working machine, comprising a table, an upright rotatable post extending above and below the table top, a traveling saw carriage provided with a saw mandrel 75
- 75 supported from the post and adjustable axially thereof, a rigid bracing-frame disposed beneath the table top and comprising upper and lower horizontally extending members and end legs, one of said legs extending diagonally, the upper horizontally extending member of the frame being provided with a split sleeve to receive the upright post and the lower member constituting a support for the lower end of the post, and means for 80
- 80 contracting the slit sleeve to clamp the post in its rotatable adjustment. 85
- 85 7. A wood working machine, comprising a table, an upright rotatable post extending above the table, a traveling saw carriage 90
- 90 provided with a saw mandrel supported from the post and adjustable axially thereof, and means for positively locking the post at different rotatable adjustments comprising a collar secured to the post and a locking 95
- 95 member engaging the collar and a part of the table in adjustments of the post to secure the saw in various cutting positions.

In testimony whereof I affix my signature.
MACKINTOSH HUTCHINSON.
